DISPENSER TOP FOR A PRESSURE CONTAINER

Philip L. Crowell and William C. Harris, Racine, Wis.,
assignors to S. C. Johnson & Son, Inc., Racine, Wis.

Filed Nov. 20, 1963, Ser. No. 77,508

Term of patent 14 years

(Cl. D58—26)

Fig. 1.

Fig. 2.

Fig. 3.

Fig. 5.

Fig. 4.

Fig. 6.

FIG. 1 is a front elevational view of a dispenser top for a pressure container embodying our new design;

FIG. 2 is a side elevational view thereof;

FIG. 3 is a rear elevational view thereof;

FIG. 4 is a top plan view thereof;

FIG. 5 is a perspective view thereof; and

FIG. 6 is a cross-sectional view thereof taken through the center.

We claim:

The ornamental design for a dispenser top for a pressure container, substantially as shown.
